ARTHUR B. PHILLIPS, OF LYNBROOK, NEW YORK

TESSELLATE PUZZLE

Application filed May 23, 1930. Serial No. 454,849.

This invention has for its object to provide a novel amusement or game means in the form of a puzzle, comprising a plurality of tile-like pieces of various sizes, the surfaces 5 of which are divided into squares, and certain of which pieces have a square of contrasting color. The tile-like pieces thus provided are capable of being assembled together in geometrical form, and the object 10 of the game or puzzle is to so assemble the pieces that no colored squares are aligned, in the finished geometrical form of the assembly, either horizontally, vertically or diagonally. 15 With the object of this invention in view, the same consists in a number of tile-like pieces of various sizes, each containing on its surface one or more squares, according to the size thereof, and certain of the pieces containing a square of contrasting color; all whereby the pieces may be interfitted together, to form in assembled relation, a tessellate pattern in which the colored squares 20 are so placed that only a single colored square is located in any one horizontal, vertical or diagonal row of squares.

The pieces may vary in number according to the number of squares to be contained in the finished tessellate pattern. Illustrative 30 of the principles of the game or puzzle, the accompanying drawings show one embodiment of the invention in which the number and arrangement of pieces is such that a tessellate pattern containing one hundred squares as a maximum is provided.

In said drawings, Figure 1 is a plan view showing the group of pieces having their surfaces divided into squares, one of which is a square of contrasting color, and Figure 2 40 is a plan view of the group of pieces having their surfaces divided into squares with none of the chosen contrasting color.

Figure 3 is a plan view illustrating the manner of initiating the assembly of pieces 45 to produce the desired tessellate pattern; Figure 4 being a plan view of such initial assembly as completed.

Figures 5 to 10 inclusive are respectively plan views showing the manner of progressively building up the assembly of pieces until

a tessellate pattern containing the maximum number of squares in desired arrangement is attained, the heavy lines in these views indicating the lines of separation between individual pieces or tiles.

Similar characters of reference are employed in the above described views to indicate corresponding parts.

When providing the game or puzzle for the production of a tessellate pattern containing one hundred squares as a maximum, the full set of pieces or tiles preferably comprises a group A providing ten pieces or tiles of various sizes, as shown in Figure 1, designated respectively by the reference numerals 55 11, 12, 13, 14, 15, 16, 17, 18, 19 and 20, and a group B providing pieces or tiles of various sizes, as shown in Figure 2, tiles of respective sizes in this group being designated by the reference numerals 21, 22, 23, 24 and 25.

In group A, the respective pieces or tiles 60 vary in length as follows:—

The piece or tile 11, is of a length whereby its surface is divided into a row of ten squares, 65 an end square 11' being of a color contrasting with that of the other squares, e. g. nine squares being white and said end square 11' black; and in like manner, the piece or tile 12 possesses nine squares, eight white and a black end square 12'; the piece or tile 13 possesses 70 eight squares, seven white and a black end square 13'; the piece or tile 14 possesses seven squares, six white and a black end square 14'; the piece or tile 15 possesses six squares, five white and a black end square 15'; the piece or tile 16 possesses five squares, four 75 white and a black end square 16'; the piece or tile 17 possesses four squares, three white and a black end square 17'; the piece or tile 18 possesses three squares, two white and a black end square 18'; the piece or tile 19 possesses two squares, one white and a black square 19' and the piece or tile 20 forms a single black square.

In group B, the respective pieces or tiles 80 also vary in length as follows:—

A piece 21 is of a length whereby its surface is divided into a row of five white squares; four pieces 22 are each of a length 85 whereby their surfaces are divided into a 90

row of four white squares; four pieces 23 are each of a length whereby their surfaces are divided into a row of three white squares; four pieces 24 are each of a length whereby 5 their surfaces are divided into two white squares; and four pieces 25, each forming a single white square.

With the pieces or tiles thus provided, the problem or puzzle for solution is to so group 10 or assemble the pieces or tiles into square geometric form in which the small black and white squares on the faces of the pieces or tiles are so related that not more than one black square appears in any single row of 15 squares running either vertically, horizontally or diagonally (i. e. taken along a line passing through diagonal corners of a black square) in the finished mosaic pattern provided thereby in the complete assembly.

20 The problem or puzzle thus provided requires the exercise of no little ingenuity and study in the solving thereof, and therefore affords considerable interest and entertainment. In its solution an initial geometric 25 form C containing sixteen surface squares is the minimum size assembly which can be produced under the requirements of the puzzle. This form may be increased in size by adding pieces or tiles to produce gradually enlarged 30 forms D, E, F, G, H and I until a maximum size assembly of one hundred surface squares is reached, when employing the set of pieces or tiles containing the members shown in groups A and B of Figures 1 and 2. It will 35 be obvious, however, that the maximum number of pieces may be less or more than shown in groups A and B, should it be desired to decrease or increase the maximum size of finished geometric form on assembly attainable therewith.

An examination of Figures 5 to 10 inclusive will clearly show how the pieces or tiles may be added to the minimum or initial form C so as to produce larger and larger geometric 45 forms or assemblies until the form or assembly of given maximum size is attained.

While I have shown the individual pieces or tiles all of rectangular form, it is not essential, in the broader aspects of my invention, that the same all be restricted to such form, since, if desired, certain of the same may be of irregular form. I have also shown in group B four single white square pieces, these may, if desired, be combined so as to 55 provide two square pieces or tiles, such as the pieces 24, in place thereof.

The arrangement of pieces or tiles as shown in groups A and B is preferable, however, since it permits, the further statement 60 in aid of the solution of the puzzle, that all pieces or tiles of group A will be disposed vertically, while all pieces or tiles of group B will be disposed horizontally, in the finished form or assembly, when the same is properly made up.

It will be obvious that modifications other than those above specified, may be made within the spirit of this invention as defined in the appended claims, hence the showing of the drawings and the description contained in the above specification are desired to be considered as illustrative and not in a limiting sense.

Having thus described my invention, I claim:—

1. A puzzle, comprising a plurality of pieces having their surfaces patterned in squares, certain of said pieces containing in their square patterned surfaces squares of contrasting color, said pieces being capable of fitting together to produce a finished geometrical form of tessellate appearance in which no squares of the contrasting color are aligned either horizontally, vertically or diagonally as taken along lines passing through diagonal corners of said squares of the contrasting color.

2. A puzzle, comprising a plurality of pieces of various lengths having their surfaces patterned in squares, certain of said pieces having squares of all one color, and other of said pieces having squares of the same and a contrasting color, said pieces being capable of fitting together to produce a finished geometrical form of tessellate appearance in which no squares of the contrasting color are aligned either horizontally, vertically or diagonally as taken along lines passing through diagonal corners of said squares of the contrasting color.

3. A puzzle, comprising a plurality of pieces having their surfaces patterned in squares, certain of said pieces containing one square of contrasting color, said pieces being capable of fitting together to form a finished tessellate mosaic in which no single vertical, horizontal or diagonal row of squares contains more than one square of contrasting color, each diagonal row of squares being interpreted as consisting of those squares that are bisected by a straight diagonal line passing through diagonal corners of all of the squares of the row.

4. A puzzle, comprising a plurality of pieces having their surfaces patterned to form one or more aligned squares, certain of said pieces having a single square of contrasting color, said pieces being capable of fitting together to form a finished tessellate mosaic in which no single vertical, horizontal or diagonal row of squares contains more than one square of contrasting color, each diagonal row of squares being interpreted as consisting of those squares that are bisected by a straight diagonal line passing through diagonal corners of all of the squares of the row.

5. A puzzle, comprising a plurality of pieces of various sizes having a surface pattern of geometrical figures, certain of said

pieces having a contrasting pattern figure, said pieces being capable of fitting together to form a plurality of finished assemblies containing horizontal, vertical and diagonal rows of pattern figures, no one of said rows containing more than one contrasting pattern figure, each diagonal row of squares being interpreted as consisting of those squares that are bisected by a straight diagonal line passing through diagonal corners of all of the squares of the row.

6. A puzzle, comprising a plurality of rectangular pieces having their surfaces respectively patterned to form one or more aligned pattern figures, certain of said pieces having a single contrasting pattern figure at an end thereof, and said pieces being capable of fitting together to form a plurality of finished assemblies containing horizontal, vertical and diagonal rows of pattern figures, no one of said rows containing more than one contrasting pattern figure, each diagonal row of squares being interpreted as consisting of those squares that are bisected by a straight diagonal line passing through diagonal corners of all of the squares of the row.

7. A puzzle, comprising a plurality of rectangular pieces of various lengths having their surfaces patterned to provide one or more squares lengthwise thereof, certain of said pieces having a single pattern square of contrasting color at the ends thereof, and said pieces being capable of fitting together to form a member of finished tessellate mosaics of varying sizes in which no single vertical, horizontal or diagonal row of squares contains more than one square of contrasting color, each diagonal row of squares being interpreted as consisting of those squares that are bisected by a straight diagonal line passing through diagonal corners of all of the squares of the row.

In testimony, that I claim the invention set forth above I have hereunto set my hand this 45 21 day of May, 1930.

ARTHUR B. PHILLIPS.
